UNITED STATES PATENT OFFICE.

PETER HAGAN, OF ELIZABETH CITY, ASSIGNOR TO WM. N. WALTON, OF NEWARK, NEW JERSEY.

IMPROVEMENT IN LAMP-CHIMNEYS.

Specification forming part of Letters Patent No. **59,389**, dated November 6, 1866.

To all whom it may concern:

Be it known that I, PETER HAGAN, of Elizabeth City, Union county, State of New Jersey, have invented a new and useful Improvement in Lamp-Chimneys; and I do hereby declare that the following is a full, clear, and exact description thereof, which will enable others skilled in the art to make and use the same, reference being had to the accompanying drawings, forming a part of this specification, in which—

Figure 1 represents a side elevation of this invention. Fig. 2 is a horizontal section of the same.

Similar letters of reference indicate like parts.

This invention relates to a lamp-chimney which is provided with a flat bulb having on its broad surfaces a series of raised circles, forming a number of reflecting-faces which diffuse the light and increase the illuminating power, and which also enable the chimney to expand and contract within certain limits, so as to prevent breakage.

A represents a lamp-chimney with a broad flat bulb, as clearly shown in Fig. 2 of this

drawing, said bulb being provided on its broad surfaces with a series of concentric circles, *a*. These circles form reflecting-surfaces, whereby the light is diffused and the illuminating power increased, and consequently a saving in oil is effected; and, furthermore, by the concentric circles the chimney is allowed to expand and contract to a certain extent, and it is less liable to break than a chimney of the ordinary construction.

My chimneys are blown in a mold. They can be made cheap, and their advantages will be readily understood from the foregoing description.

I claim as new and desire to secure by Letters Patent—

A chimney having on its bulb a series of rings or circles, substantially as and for the purpose set forth.

The above specification of my invention signed by me this 13th day of July, 1866.

PETER HAGAN.
